UNITED STATES PATENT OFFICE.

WILLIAM J. SCOTT, OF WASHINGTON, DISTRICT OF COLUMBIA.

SOUND-INTERFERENCE ELIMINATOR.

Application filed December 9, 1922. Serial No. 605,801.

The invention relates to tone clarifying and interference eliminating means and has for its object to provide an instrument which is selective in its action and which is adapted in operation to eliminate or subdue mechanical sounds or noises, of an abrupt, explosive or discontinuous character, such as those of machinery, gun fire electrical static and the like, and differentiate, prolong, convey, emphasize and sustain for delivery to the listener or receiving operator the distinguishable musical, singing, continuous or uniformly pitched sounds or tones such as those of the human voice, musical instruments, radio or wireless telephone or telegraph messages or signals and the like, to the end that the apparatus in its various available adaptations of principle may be used either for the direct conveyance of spoken messages between occupants of the same aircraft, or as a receiving instrument between the occupants of different aircrafts or in the vicinity of machinery producing an overwhelmingly obstructive or confusing noise, or at the receiving station of a radio or wireless system.

With this object in view the invention consists in a construction and combination of parts of which a preferred embodiment is shown in the accompanying drawings, wherein:

Figure 1 is a longitudinal sectional view of a typical embodiment of the invention in a relatively simple form adapted for example for use between joint occupants of the same aircraft as a means of facilitating uninterrupted conversational communication and constituting a refinement based on the same principle of operation disclosed in my co-pending application Serial No. 440,995, filed Jan. 29, 1921.

Figure 2 is a cross sectional view of the same on the plane indicated by the line 2--2 of Figure 1.

Figure 3 is a longitudinal sectional view of the modification constituting a further refinement of the structure which is particularly designed for use in connection with wireless receiving stations and wherein a graduated expansion or dispersion of the sound conveying air column in the transmitter chamber is effected in advance or on the transmission side of the subdividing diaphragm or element.

Figure 4 is a transverse sectional view of the receiving tube correspondingly adjusts

on the plane indicated by the line 4--4 of Figure 3.

Whether the instrument is used in an intercepting relation with a direct tubular line of communication for the voice (such as a speaking tube) between the speaker and the auditor, or in connection with a wireless receiving station, it embodies, essentially, a sound conductor or conveyor having a sound transmitting member and a communicating sound receiving member, each having certain mechanical characteristics for affecting the contained column of air and hence the passage of the sound waves therethrough, and a subdividing or selecting medium interposed, and serving to mark the line of distinction between the transmitting and the receiving members of the conductor or conveyor, and hence between the transmitting and receiving portions of the column of air contained in said conductor or conveyor.

In the embodiment of the instrument which is shown in Figures 1 and 2 the transmission tubes 10 by which the sounds to be transmitted enter the instrument, communicate with an enlarged expansion or dispersion chamber 11, and in the path of outlet from the chamber 11 is a sub-dividing or selecting medium particularly represented by a diaphragm 13 having perforations 14 from which extend tubes 15 which open into an expansion chamber 16 bounded by a diaphragm 17 also having perforations with which communicate tubes 18 which are grouped or assembled in graduated or step by step relation to correspondingly assemble or reunite the elements of the air column separated by passing through the diaphragm until they ultimately combine in the main receiving tube 19 which in turn communicates with the outlet or ear tubes 20. The receiving tube is preferably of telescoping construction to permit of elongation through exteriorly accessible means represented by the lever 21 fulcrumed upon a suitable standard 22 and having connected therewith a rod 23 extending from the outer member of the receiving tube, and the grouped tubes leading into the receiving tube and which provide for a graduated or step by step enlargement of the passages between the expansion chamber 16 and the receiving tube preferably carrying the diaphragm 17 so that the adjustment of the movable member of the receiving tube correspondingly adjusts

105

110

the diaphragm 17 to vary the capacity of the expansion chamber 16. As the receiving tube is elongated the capacity of the expansion chamber is increased.

5 The sub-dividing openings or passages in the diaphragma 13 are graduable in area by radiating means represented by a rotary disk or damper 24 provided with any suitable externally accessible manually actuatable 10 adjusting mechanism 25 and having perforations 26 arranged to register with those of the diaphragm and adapted by the turning of the disk to be moved more or less out of registration therewith so as to vary the effective exposure of the openings and the extent to which sounds may be communicated from the transmitting member of the conductor to the receiving member thereof.

Thus the column of air in the instrument 20 is first expanded or dispersed in the transmitting member of the instrument to correspondingly expand or disperse sound waves entering the same and which more or less are confused by distracting and confusing noises, and is then subdivided by passage through the diaphragm, following which the elements of the air column and sound waves are reassembled or reunited or condensed gradually to resume a unitary condition in the outlet element or chamber 16 constituting the receiving member of the conductor. In its course through the circuitous, more or less elongated and gradually expanded and assembling passage, the distracting and irrelevant sounds are eliminated or lost or subdued, and only the musical or continuous or voice sounds are preserved and maintained for presentation to the ear of the auditor.

40 The transmission tubes, of which, like the receiver or ear tubes, a plurality may be provided, are shown expanded progressively in the direction of progress of the sound waves, while the branches or assembling tubes representing the receiving member of the sound conductor are graded in diameter or are progressively increased in capacity as the number thereof is diminished until the unitary structure as at the inlet, is 45 reached in the main receiving tube 19.

In the modification shown in Figures 3 and 4, however, while the gradable subdividing medium 13^a of Figures 1 and 2 is employed, with an expansion chamber 16^a bounded by a second or supplemental subdividing diaphragm 17^a, there is included a variation of the transmitting member of the sound conductor wherein provision is made for a succession of graded expansions or enlargements of the column of air and hence of the vibration thereof under the impulse of sound waves entering the instrument. These expansions or enlargements 50 are of bell or horn shape as shown at 27 leading from a plurality of sound inlet tubes

28 in which may be arranged microphones or like transmitters 29 for use in receiving wireless messages. These gradually expanded transmitter members 27 communicate with a common bell-mouthed element 30 located adjacent to the plane of the sub-dividing medium represented by the diaphragm 13^a.

Moreover in this form of the apparatus the receiving member of the sound conductor is provided with an additional expansion chamber 32 in communication with the chamber 16^a by means of tubes carried by the diaphragm 17^a and bounded by a diaphragm 33 with which are connected the 30 graduated tubes 34 in communication with the receiving tube 35 which as described in connection with the form shown in Figures 1 and 2 is of extensible or telescoping construction. The tubes 34 are graduated increasingly in diameter and are reduced in number as previously described in reference to the corresponding tubes of the form shown in Figure 1 and ultimately merge 35 into the main receiving tube for the purposes also heretofore explained of effecting a graduated re-assembling or condensation of the previously subdivided or dispersed elements of the sound wave carrying column 40 of air.

In this form of the apparatus the ear tubes are indicated at 20^a and a microphone 36 is arranged at the inlet end of the receiving tube 35 which is adjustable through mechanism 37 corresponding with that previously described.

It has been demonstrated by actual tests both in simple voice or vocal transmission and in connection with wireless receiving apparatus that a clear and uninterrupted reception of a message can be obtained in the presence of mechanical, static and like confusing sounds and agencies which otherwise are sufficient to entirely overwhelm the message and render it indistinguishable to even the most expert operator.

Having described the invention, what is claimed as new and useful is:—

1. An instrument for selectively distinguishing the tones of a transmitted message from contemporaneous unrelated sounds, the same having a sound transmitting passage and a sub-dividing diaphragm intercepting the same, the passage being provided in advance of the plane of the diaphragm with graduated expanding means and in rear thereof with graduated condensing means.

2. An instrument for selectively distinguishing the tones of a transmitted message from contemporaneous unrelated sounds, the same having a sound conducting passage provided progressively with means for dispersing and reassembling the sound carrying medium and a subdividing element arranged between said means and having minute se-

- lecting openings which are respectively graduable in area.
3. An instrument for selectively distinguishing the tones of a transmitted message from contemporaneous unrelated sounds, the same having a sound conducting passage, and a sub-dividing medium intercepting the same, said passage being provided with a graded enlargement of bell or horn shape with its larger end directed toward and in communication with the inlet thereof.
4. An instrument for selectively distinguishing the tones of a transmitted message from contemporaneous unrelated sounds, the same having a sound conducting passage, and a sub-dividing medium intercepting the same, said passage being provided with a series of graded expansions or enlargements extending from the sub-dividing medium to the inlet.
5. An instrument for selectively distinguishing the tones of a transmitted message from contemporaneous unrelated sounds, the same having a sound conducting passage, and a sub-dividing medium intercepting the same, said passage being provided with a series of graded expansions or enlargements of bell or horn shape, the initial units of said series having their larger ends communicating with the inlets and the final of said series having its larger end adjacent said sub-dividing means.
6. An instrument for selectively distinguishing the tones of a transmitted message from contemporaneous unrelated sounds, the same having a sound conducting passage, a sub-dividing medium intercepting the same, said passage being provided with a succession of graded expansions or enlargements of bell or horn shape communicating with inlets at their larger ends, and a common bell mouthed element located adjacent the plane of the sub-dividing medium and communicating with said enlargements.
7. An instrument for selectively distinguishing the tones of a transmitted message from contemporaneous unrelated sounds, the same having a sound conducting passage provided progressively with means for dispersing and reassembling the sound carrying medium, and a sub-dividing element disposed between the dispersing and reassembling means and having minute selecting openings, said sub-dividing element consisting of relatively movable members for varying the relative positioning of the corresponding openings in each for the variation of the area of the openings in the sub-dividing element.
8. An instrument for selectively distinguishing the tones of a transmitted message from contemporaneous unrelated sounds, the same having a sound conducting passage provided progressively with means for dispersing and reassembling the sound carrying medium, and a sub-dividing element disposed between said dispersing and reassembling means and having minute selecting openings variable in area, said sub-dividing element consisting of a fixed diaphragm provided with perforations and a rotary disk carried by the diaphragm and also provided with perforations and a manually actuatable device for effecting its adjustment.
9. An instrument for selectively distinguishing the tones of a transmitted message from contemporaneous unrelated sounds, the same having a sound conducting passage, and a sub-dividing medium intercepting the same, said passage being provided with a series of graded expansions or enlargements extending from the sub-dividing medium to the outlet, and said sub-dividing medium being provided with minute selecting openings, and means for varying the effective area thereof.
10. An instrument for selectively distinguishing the tones of a transmitted message from contemporaneous unrelated sounds, the same having a sound conducting passage, a sub-dividing medium intercepting the same, said passage being provided with a succession of graded expansions or enlargements of bell or horn shape communicating with the inlet at their larger ends, and a common bell mouth element located adjacent the plane of the sub-dividing medium and disposed with its larger end adjacent said medium and with its smaller end in communication with said enlargements.

In testimony whereof he affixes his signature.

WILLIAM J. SCOTT.
